United States Patent Office

Des. 212,512
Patented Oct. 22, 1968

212,512

AIRCRAFT

Theodore R. Smith, Los Angeles, Calif., assignor to Ted Smith Aircraft Co., Inc., Northridge, Calif., a corporation of California

Filed Feb. 21, 1966, Ser. No. 1,123

Term of patent 14 years

(Cl. D71—1)

Fig. 1

Fig. 2

FIGURE 1 is a perspective view of an aircraft, showing my new design;

FIGURE 2 is a top plan view thereof;

FIGURE 3 is a bottom plan view thereof;

FIGURE 4 is a side elevational view thereof;

FIGURE 5 is a front elevational view thereof; and

FIGURE 6 is a rear elevational view thereof.

The dominant features of my design are shown in full lines; and, the dotted line showing of the propeller in motion in FIGS. 1, 5 and 6 is so shown for illustrative purposes only.

I claim:

The ornamental design for an aircraft, substantially as shown and described.
